UNITED STATES PATENT OFFICE.

FAYETTE C. NEWTON, OF WEST SPRINGFIELD, MASSACHUSETTS, ASSIGNOR TO THE
HART & HEGEMAN MANUFACTURING COMPANY, OF HARTFORD, CONNECTICUT,
A CORPORATION OF CONNECTICUT.

ELECTRIC SWITCH.

1,060,207.

Specification of Letters Patent. Patented Apr. 29, 1913.

Application filed June 30, 1910. Serial No. 569,734.

To all whom it may concern:

Be it known that I, FAYETTE C. NEWTON, a citizen of the United States, and a resident of West Springfield, in the county of 5 Hampden, State of Massachusetts, have invented certain new and useful Improvements in Electric Switches, of which the following is a specification.

The invention relates particularly to an 10 electric switch of the push button type, for instance such as shown in the patent to Monroe Guett, No. 972,365, dated Oct. 11, 1910; and the object of the invention is to improve the construction of switches of this 15 character, and particularly to provide a mechanism whereby two or more circuits can be controlled by controlling the movements of the switch plates.

Referring to the drawings: Figure 1 is a 20 side view of a switch embodying my invention some parts being removed to more clearly show the structure. Fig. 2 is an end view of a part of the switch illustrating my invention. Fig. 3 is a transverse section 25 view of the interior of the receptacle adapted for use with my switch. Fig. 4 is a side elevation of a switch embodying my invention in its intermediate position. Fig. 5 is a diagrammatical view of the switch showing 30 the circuits when the parts are in inactive position. Fig. 6 is a similar view when the parts are in intermediate position. Fig. 7 is a similar view showing the parts in the other extreme position.

Referring to the drawings 1-2 denote 35 the push buttons, 3, 3' the switch plates, 4 the oscillating plate with which the push buttons are connected; 5-6 two locking flanges on this oscillating plate, 7 a locking 40 member pivoted on the frame having radial arms 8-9, one of which, 8, has locking projections 10-11, adapted to coöperate with the flanges 5-6 respectively, on the oscillating plate 4, the other arm 9 carrying a pin 12, which is in engagement with a part 45 secured to the poles. The usual snap mechanism including a spring indicated at 13 is interposed between the oscillating plate 4 and the switch plates 3.

In the operation of this device it will be 50 seen that if the push button 1 is pressed down, the oscillating plate 4, connected with it, will be turned on the spindle, moving the flange 5 under the locking projec-

tion 11, and at the same time one end of the 55 actuating spring 13 is moved by an arm on the oscillating plate. The poles are held against movement because they are engaged by the pin 12 mounted on the arm 9 of the locking member 7, and as the other end of 60 the spring is held by another arm fixed to the poles, the movement of the oscillating plate 4 winds up or makes tense the spring 13. When the flange 5 passes from under the projection 11, the locking member 7 is 65 released, releasing the poles and permitting the spring 13 to move the poles. Since the poles are released when the oscillating member 4 has made about one-half of its complete movement, the spring has been extended just about one-half as much as would ordinarily be the case. By the time the locking projection 11 has passed through the notch between the flanges 5, 6, the spring 70 has lost its power and the poles stop in this 75 intermediate position. If the push button is now pressed still further, the flange 6 will pass underneath the locking projection 10 which again holds the switch plates or poles stationary, and at the same time tensioning the spring until the flange 6 passes from under the projection 10, when the spring throws the switch plates to their extreme position. Of course, as the push button 1 is being depressed, the push button 2 80 is being released. If now, the push button 2 is depressed, the operation is repeated, but in a reverse direction. The under part of the flange 6 now travels over the upper end 85 of the locking projection 10 until the switch 90 plate moves to its intermediate position, and then the under part of the flange 5 rides over the upper end of the locking projection 11 until the switch plates are again released.

In one extreme position of the switch plates, indicated diagrammatically in Fig. 5, which may be termed the inactive position, it will be noted that the switch plates 3, 3' are out of engagement with the contacts 15-16 and 17-18, and the two lights L, L' are out. In the intermediate position illustrated diagrammatically in Fig. 6 the switch plate 3, is still out of engagement with contacts 17-18 while the switch plate 10, 3' is in contact with the upper ends of the contacts 15-16 and the light L' is lighted. In the other extreme position illustrated di-

agrammatically in Fig. 7 the switch plates 3, 3' are in engagement with the contacts 17-18 and 15-16, and the contacts 15, 17 being connected both lights L, L' are lighted. When the switch plate 3' moves from the position of Fig. 6 to that of Fig. 7 it always remains in engagement with the contacts 15-16 so that the light L' is kept lighted during this shift in the position of the switch plate.

a—b denote the line wires.

Switches of this type are largely used in connection with electroliers provided with two separate sets of lights so that the circuits of both sets of lights can be separately controlled.

I claim:

1. In an electric switch a pair of switch plates adapted for movement in either direction between two extreme positions, and means for stopping said switch plates at an intermediate point, in combination with a set of circuit terminals adapted to be engaged by one only of said switch plates when 25 in their intermediate position, and a second set of circuit terminals adapted to be engaged by the other switch plate in one of its extreme positions.

2. The combination with a receptacle having sets of terminals for separate electric circuits, of a switch mechanism located in said receptacle comprising an oscillating switch plate for each circuit, operating mechanism for said switch plates and a reciprocating handle to actuate said operating mechanism, of terminals being displaced relatively to one another in the direction of movement of the switch plates, whereby said circuits may be closed and opened separately.

3. In an electric switch the combination with a plurality of oscillatory switch plates, a plurality of stops connected with said switch plates, a plurality of locking members connected with said operating member, and adapted to coöperate with the plurality of stops successively, of a receptacle in

which said switch is mounted and a plurality of sets of terminals for separate circuits in said receptacle.

4. In an electric switch the combination with a receptacle having sets of terminals for separate circuits, of a switch mechanism located in said receptacle, an oscillating plate for each set of terminals, an operating handle, means for holding said switch plates against movement during the initial movement of said operating handle, means actuated by said handle for releasing said holding means, and means for stopping the movement of said switch plates at a point intermediate of the extreme positions of said switch plates.

5. In an electric switch of the push button type adapted for the controlling of separate circuits, a pair of oscillating switch plates, an operating member, a spring interposed between and connecting said switch plates and operating member, push buttons connected with said operating member, a controlling member connected with said switch plates, and a series of stops on said operating member adapted to be engaged successively by said controlling member, whereby said plates may be stopped at a point intermediate of their two extreme positions when moving in either direction.

6. In a switch of the character described, a pair of switch plates, an operating member, a spring interposed between and connecting said switch plates and operating member, push buttons connected with said operating member, a pair of locking flanges on said operating member, a controlling member connected with said switch plates, and a pair of locking projections on said controlling member adapted to coöperate with said locking flanges for the purposes specified.

FAYETTE C. NEWTON.

Correction in Letters Patent No. 1,060,207.

It is hereby certified that in Letters Patent No. 1,060,207, granted April 29, 1913, upon the application of Fayette C. Newton, of West Springfield, Massachusetts, for an improvement in "Electric Switches," an error appears in the printed specification requiring correction as follows: Page 2, line 36, before the word "of" insert the words *said sets*; and that the said Letters Patent should be read with this correction therein that the same may conform to the record of the case in the Patent Office.

Signed and sealed this 19th day of August, A. D., 1913.

[SEAL.]

THOMAS EWING,

Commissioner of Patents.
